UNITED STATES PATENT OFFICE.

MILTON D. MESEROLE, OF WEST HAVEN, CONNECTICUT, ASSIGNOR, BY MESNE ASSIGNMENTS, TO THE JAMES F. MOLLOY CO., OF NEW HAVEN, CONNECTICUT, A CORPORATION.

BELT-BUCKLE.

1,097,182

Specification of Letters Patent. Patented May 19, 1914.

Application filed May 26, 1913. Serial No. 769,891.

To all whom it may concern:

Be it known that I, MILTON D. MESEROLE, a citizen of the United States, residing at West Haven, in the county of New Haven and State of Connecticut, have invented a new and useful Improvement in Belt-Buckles; and I do hereby declare the following, when taken in connection with the accompanying drawings and the characters 10 of reference marked thereon, to be a full, clear, and exact description of the same, and which said drawings constitute part of this application, and represent, in—

Figure 1 a reverse view of a buckle constructed in accordance with my invention and shown as applied to a belt which it is adjusted to grip. Fig. 2 an edge view thereof. Fig. 3 a view thereof in central longitudinal section. Fig. 4 a sectional view thereof in its open position and with the belt withdrawn. Fig. 5 a detached view of the buckle-lever blank. Fig. 6 a view in longitudinal section of one of the modified forms which my improved buckle may assume.

25 My invention relates to an improvement in belt-buckles, the object being to produce a simple, compact, reliable and convenient buckle of attractive appearance and constructed with particular reference to being 30 adapted, without injury, to receive belt straps varying widely in thickness.

With these ends in view my invention consists in a buckle having certain details of construction and combinations of parts as 35 will be hereinafter described and pointed out in the claim.

In carrying out my invention as herein shown, I employ an oblong rectangular sheet-metal buckle-frame 2, longitudinally 40 and transversely crowned and formed upon its upper and lower edges with inwardly turned flanges 3 having centrally arranged trunnions 4 perforated for the reception of trunnions 5 formed at opposite points upon and 45 near the free end of the outer leaf or member 6 of a yielding buckle-lever formed from a blank 7 (Fig. 5) folded transversely about midway of its length, and having its inner leaf or member 8 formed at its free end with 50 a gripping-edge 9 which is engaged with the belt 10 in position to force the same against the inner face of the buckle-frame 2 as clearly shown in Fig. 3. The buckle-lever is thus pivoted upon the inner face of the

buckle-frame and the bend of the lever constitutes a spring for it. The outer member 6 of the buckle-lever is formed, as shown, with ears 11 located at opposite points upon its edges and perforated as at 12 for the reception of the trunnions 13 of a fastening-lever 14 by means of which the fixed end 15 of the belt 10 is secured in place. The construction thus far described is old and well known. My invention in particular consists in interposing a buffer of suitable description between the two members 6 and 8 of the buckle-lever so as to adapt the same to yield more or less without being set, and thus injured, to provide for the accommodation of straps of different thickness.

As shown in Figs. 1, 2, 3 and 4, the outer member 6 of the lever is struck outward to form a pocket 16 for the reception of a buffer in the form of a small rubber button 17 which is thus located between the members 6 and 8 of the buckle-lever and yields under the pressure of the gripping-edge 9 and member 8, more or less, according to the thickness of the strap.

Initially the buckle is constructed for thin belts, or belts of medium thickness, which impose little pressure upon the button 17. In case, however, a thick belt should be used, the button 17 yields and prevents the edge 9 of the member 8 from being set and thus 85 disqualified from again gripping a thin belt or a belt of medium thickness.

The modified construction shown by Fig. 6, illustrates the employment of a buffer in the form of a small helical spring 18 in the place of the rubber button 17. In the said modified construction also the fastening lever 14 of the other figures, is replaced by a permanently applied wire loop 19 through which the fixed-end 15 of the belt 10 is 95 passed and folded upon itself and sewed by stiches 21 in the well known manner.

I claim:

In a belt buckle, the combination with the frame thereof, of a sheet-metal buckle-lever folded upon itself and comprising an inner and outer leaf normally separated from each other by an accommodation space, the free end of the said inner leaf having a gripping-edge which co-acts with the inner face of the said frame for gripping the webbing, and the outer leaf being pivotally connected at its inner end with the said frame

and provided with a pocket to increase the depth of the said space, and a buffer inserted into the said pocket and yielding to provide for the accommodation of buckle-straps of varying thickness without setting the leaves of the buckle-lever.

In testimony whereof, I have signed this

specification in the presence of two subscribing witnesses.

MILTON D. MESEROLE.

Witnesses:

LORENZO L. WILLIAMS,
LEON M. MOLLOY.
